DESIGN FOR A LAMP STANDARD

John R. Crawford, Los Angeles, Calif.

Application December 8, 1945, Serial No. 124,556

Term of patent 3½ years

(Cl. D48—20)

To all whom it may concern:

Be it known that I, John R. Crawford, a citizen of the United States, residing in Los Angeles, in the county of Los Angeles and State of California, have invented a new, original, and ornamental Design for a Lamp Standard, of which the following is a specification, reference being had to the accompanying drawing, forming part thereof.

Fig. 1 is an elevational view of a lamp standard, showing my new design.

Fig. 2 is a plan view taken on the line 2—2 of Fig. 1.

The dominant features of my design reside in

the portions shown in full lines. The drawing is lined to indicate color contrast.

I claim:

The ornamental design for a lamp standard, substantially as shown and described.

JOHN R. CRAWFORD.
